US0D1104853S

(12) **United States Design Patent** (10) **Patent No.:** **US D1,104,853 S**
(45) **Date of Patent:** **** Dec. 9, 2025**

(54) **PLANT TROUGH**

(71) Applicant: **URBIDERMIS, S.L.**, La Roca del Vallès (ES)

(72) Inventor: **Laia Crous Bonamusa**, Barcelona (ES)

(73) Assignee: **URBIDERMIS, S.L.**, La Roca del Valles (ES)

(**) Term: **15 Years**

(21) Appl. No.: **35/521,420**

(22) Filed: **May 24, 2024**

(80) **Hague Agreement Data**

Int. Filing Date: **May 24, 2024**

Int. Reg. No.: **DM/237826**

Int. Reg. Date: **May 24, 2024**

Int. Reg. Pub. Date: **Jun. 21, 2024**

(51) **LOC (15) Cl.** **11-02**

(52) **U.S. Cl.**

USPC **D11/156**
